(57) CLAIM

I claim the ornamental design for a template for making bags, as shown.

DESCRIPTION

The patent or application file contains at least one drawing executed in color. Copies of this patent or patent application publication with color drawing(s) will be provided by the Office upon request and payment of the necessary fee.

FIG. 1 is a perspective view of a template for making bags according to my new design;

FIG. 2 is a front view of the template;

FIG. 3 is a rear view of the template;

FIG. 4 is a top plan view of the template;

FIG. 5 is a bottom view of the template;

FIG. 6 is a left side view of the template; and,

FIG. 7 is a right side view of the template.
